SEED DRILL SHOE REGULATOR

Filed May 4, 1929

INVENTOR
Mike Chicolsky

By *J. A. Fowler*,
Attorney

UNITED STATES PATENT OFFICE

MIKE CHICOLSKY, OF SIFTON, MANITOBA, CANADA

SEED-DRILL-SHOE REGULATOR

Application filed May 4, 1928. Serial No. 275,243.

This present invention relates to new and useful improvements in a seed drill shoe regulator and has for its primary object the provision of a simple and inexpensive structure which may be readily incorporated in the seed drill of conventional type without materially altering the construction or substantially increasing the cost thereof.

Another object of the invention resides in the provision of a seed drill shoe regulator which may be readily applied and the necessary manual adjustments made as required to regulate the depth of operation of the shoe, without the employment of special tools or an experienced mechanic.

A further object of the invention resides in the provision of a seed drill shoe regulator of the character stated which may be readily adjusted on the shoe for riding on the ground surface and thus regulating the depth of travel of the shoe, in the ground, simply by changing the position of the adjustable sliding wedge constituting the regulating member of the new structure and operable between the edge of the shoe and the surface engaging member.

A still further object of the invention resides in the provision of a seed drill shoe regulator of the character stated which is of such construction that the sliding wedge may be readily adjusted to raise or lower the surface engaging member on the shoe and then locked in adjusted position to assure operation of the shoe at a uniform depth throughout the operation of the seed drill, until a new adjustment is made by changing the position of the sliding wedge.

To the accomplishment of these and related objects as will become apparent as the description proceeds, my invention resides in the construction, combination and arrangement of parts as shall be hereinafter more fully described, illustrated in the accompanying drawings, and pointed out in the claims hereunto appended.

The invention will be best understood and can be more clearly described when reference is had to the drawings forming a part of this disclosure wherein like characters indicate like parts throughout the several views.

In the drawings:—

Figure 1 is a side elevation, showing my invention in one of its adjusted positions on a conventional seed drill shoe.

Figure 2 is a similar view, showing the invention in a different adjustment.

Figure 3 is an enlarged perspective of the ground surface engaging member.

Figure 4 is a similar view of the adjustable sliding wedge.

Figure 5 is a similar view of a special flanged washer constituting a part of the tension regulating means for the ground surface engaging member.

Referring more in detail to the drawings, it is to be noted that the depth at which the shoe 12 of the seed drill 11 operates below the ground surface, is regulated by the position of the ground surface engaging member 13 vertically of the shoe 12 and with respect to the lower working edge of the latter, as will be clearly understood as the description proceeds.

The surface engaging member 13 is in the form of a longitudinally curved strip of metal or other suitable material and has its upper end secured to the inclined curved suspending bar 14 connecting with the upper forward corner of the shoe 12. The pivot pin 15 employed for this purpose is extended transversely through the bar 14 and through a pair of parallel ears bent up from the side edges of the strip 13, near the end thereof and engaged against the sides of the bar 14 and over the top thereof. The tension of the strip 13 is regulated by an expansion spring 17 on the bolt 18 directed upwardly through the strip 13, a short distance from the upper end thereof and then through the bar 14. The lower end of the spring 17 bears against the special washer 19 on the bolt 18 and having down-turned side flanges 19^a engaging the sides of the bar 14. An appropriate stop nut 20 is secured on the upper extremity of the bolt 18 and serves as an adjustable bearing for the upper end of the spring 17 for regulating the tension thereof and the consequent tension on the strip 13.

The strip 13 is split or bifurcated inwardly from its lower free end along its longitudinal

centre for about one-half the length thereof, thus providing the spaced legs 21 which work on the opposite sides of the shoe 12 and ride on the ground surface at all times, during operation of the seed drill. Upstanding, inclined flanges 22 are provided on the legs 21, with spaced teeth 23 on their rearwardly inclined upper edges. The flanges 22 are shown as being extended from the outer longitudinal edges of the legs 21 and bent back over the upper faces thereof to the inner longitudinal edges of the legs 21 and then directed upwardly in parallel spaced relation.

The adjustable regulating member is in the form of a sliding wedge 24 which is elongated and works between the curved, inclined lower face of the shoe 12 and the upper face of the strip 13. The sliding wedge 24 is bifurcated from its lower rear end for the greater portion of its length, thus providing the arms 25 which extend on the opposite sides of the shoe 12, above the legs 21 of the strip 13, when the sliding wedge is in operative position. Two spaced pairs of guide fingers 26 are carried on the arms 25, rising from the inner edges thereof, at the opposite ends of the arms 25. The guide fingers 26 are shown as extending from the outer edges of the arms 25 and being brought back over the upper face of the arms 25 to the inner edges thereof and then directed upwardly. Two pairs of outwardly directed locking fingers 27 are also provided on the outer edges of the arms 25 for engagement between and co-operation with the teeth 23 on the flanges 22 of the legs 21 of the strip 13 to regulate the position of the latter and lock the same in adjusted position, the forward solid portion of the sliding wedge 24 working between the opposed faces of the shoe 12 and the strip 13 to force lowering or permit raising of the legs 21 of the strip 13 on the shoe 12 and thus adjust and regulate the depth of operation of the shoe in the soil.

As the construction of the device has thus been described in detail, brief reference is now had to its use and mode of operation: The spring 17 tends to draw the strip 13 upwardly, thus raising the legs 21 thereof, on the shoe 12 and permitting the latter to ride deep in the soil, as indicated in Figure 1 of the drawings. Under such conditions, the adjustable regulating member 24 is in its extreme forward or uppermost position. When it is desired to raise the shoe 12 and prevent it from riding so deep in the soil, this is accomplished by adjusting the legs 21 of the strip 13 in a lower position on the shoe 12. The adjustment is made by disengaging the locking fingers 27 of the adjustable regulating member 24 from the teeth 23 of the flange 22 on the legs 21 and sliding the latter rearwardly, thus forcing the strip 13 downwardly on the opposite sides of the shoe 12. When the desired adjustment is made, the locking fingers 27 are permitted to again engage the

teeth 23 and thus lock the parts in the readjusted position. As the legs 21 of the strip 13 always ride on the surface of the ground, during operation of the device, the depth of travel of the shoe in the soil may be readily regulated, as desired, by the simple adjustment of the position of the adjustable regulating member 24. It will also be apparent that the spring 17 serves to constantly retain the desired tension on the strip 13 and thereby co-operate with the member 24 in keeping the legs 21 of the said strip 13 in adjusted position with respect to the lower curved edge of the shoe 12.

From the foregoing description taken in connection with the accompanying drawings, it will be manifest that a seed drill shoe regulator is provided that will fulfill all the necessary requirements of such a device, but as many changes could be made in the above description and many apparently widely different embodiments of my invention constructed within the scope of the appended claims without departing from the spirit or scope thereof, it is intended that all matters contained in the said specification and drawings shall be interpreted as illustrative and not in a limited sense.

Having thus described my invention what I claim as new and desire to secure by Letters Patent is:—

1. A seed drill shoe regulator including a ground surface engaging member straddling said shoe and adjustable vertically thereof; and a wedge member adjustable along the lower edge of said shoe for varying the position of said ground surface engaging member on said shoe and thus regulating the depth of travel of the said shoe in the soil.

2. A seed drill shoe regulator including the combination with the shoe; of a ground surface engaging member adjustable vertically of said shoe; and a wedge member adjustable between said shoe and said ground surface engaging member to adjust the position of said ground surface engaging member on said shoe and thus regulate the depth of travel of said shoe in the soil.

3. A seed drill shoe regulator including the combination with the shoe and the supporting means therefor; of a ground engaging member pivoted to said supporting means; said member having a bifurcated portion adjustable vertically on said shoe to regulate the depth of travel of said shoe in the soil; a wedge member adjustable between said shoe and said ground surface engaging member; and tension regulating means for said ground surface engaging member.

4. A seed drill shoe regulator including the combination with the shoe and the supporting means therefor; of a ground surface engaging member pivoted to said supporting means and having a bifurcated portion adjustable vertically on said shoe; said bifur-

cated portion having upstanding flanges with teeth on their upper edges, on either side of said shoe; a wedge member adjustable between opposed portions of said shoe and said ground surface engaging member to control the position of the latter vertically of said shoe; and tension regulating means for said ground surface engaging member.

5 In testimony whereof I hereunto affix my
10 signature.

MIKE CHICOLSKY.
